UNITED STATES PATENT OFFICE.

GEORGE D. WEAVER, OF MYRTLE CREEK, OREGON.

LAND SCRAPER.

Application filed September 1, 1923. Serial No. 660,614.

To all whom it may concern:

Be it known that I, GEORGE D. WEAVER, a citizen of the United States, residing at Myrtle Creek, in the county of Douglas and State of Oregon, have invented certain new and useful Improvements in Land Scrapers, of which the following is a specification.

My invention relates to ground scraping or leveling apparatus.

10 An important object of the invention is to provide an apparatus of the above mentioned character, adapted particularly for use in building or grading roadways, while not necessarily restricted to this use.

15 A further object of the invention is to provide apparatus of the above mentioned character, having means for holding the scraping element in a forwardly inclined position, at the starting loading operation, and 20 to permit of the gradual rearward tilting of the scraping element, as the same receives the load, such tilting operation being automatically effected by the weight of the load.

25 A further object of the invention is to provide apparatus of the above mentioned character, so constructed that the scraping element will automatically tilt rearwardly, when loaded beyond a predetermined capacity, thereby elevating the forward cutting edge of the scraping element, for discontinuing the loading action.

30 A further object of the invention is to provide apparatus of the above mentioned character, having means whereby the scraping element may be released and dumped, after or before complete loading, at the will of the operator.

35 Other objects and advantages of the invention will be apparent during the course of the following description.

In the accompanying drawings forming a part of this specification, and in which like numerals are employed to designate like parts throughout the same,

45 Figure 1 is a plan view of apparatus embodying my invention,

50 Figure 2 is a side elevation of the same, showing the parts in the starting loading position,

55 Figure 3 is a central longitudinal section taken on line 3—3 of Figure 1, showing the parts in a similar position,

Figure 4 is a similar view taken on line 3—3 of Figure 1, showing the parts shifted to the loaded position.

55 Figure 5 is a similar view showing the parts shifted to the unloading position,

Figure 6 is a side elevation of the guide-support or housing, showing the associated elements in the shifted and tripped positions,

60 Figure 7 is a transverse section taken in line 7—7 of Figure 2,

65 Figure 8 is a similar view taken on line 8—8 of Figure 2,

Figure 9 is a side elevation of a support element or yoke, and,

70 Figure 10 is a detail section through one end of the cross beam, showing the clamp means therefor.

In the drawings, wherein for the purpose of illustration is shown a preferred embodiment of my invention, the numeral 15 designates a scraping element or pan of any well known or preferred type. This scraping element is provided at its ends with 75 runners 16, rigidly attached thereto, as shown at 17 and 18. These runners embody front vertical portions 19 and upper approximately horizontal portions 20, as shown.

80 Extending across the top of the scraping element 15 is a horizontal beam or support 21, which is mounted upon the horizontal portions 20 of the runners. I prefer to provide the beam 21 with L-shaped clamping bolts 22, Figure 10, adapted to engage beneath the horizontal portions 20, and to fit within selected notches 23, as shown.

85 Arranged in advance of the scraping element 15 and longitudinally of the direction of draft, is a slightly inclined support-guide or housing 24, preferably formed of a section of strap iron, bent upon itself providing a rear end 25, connecting the sides of the support-guide. The forward end of this support-guide is preferably open, and a transverse plate 26 is arranged between the ends of the sides of this support-guide,

90 near and spaced from the forward ends thereof, rigidly attached thereto by any suitable means.

95 Mounted to slide within the support-guide or housing 24 with relation thereto, is a drawbar 27 slidable within openings 28 and

29, formed in the plates 25 and 26 respectively. A roller 30 is carried within the rear end of the support-guide, above the drawbar 27, and a roller 31 is carried in the forward 5 end of the support-guide, preferably in advance of the plate 26, and engages above the drawbar 27, as shown. A suitably stiff coil spring 32, surrounds the drawbar 27, within the support-guide or housing, and its rear 10 end engages the stop element or plate 33, held against rearward movement with respect to the drawbar, by means of a transverse pin 34, carried by the drawbar. The forward end of the spring engages against 15 the transverse plate 26.

Connected with the forward end of the drawbar 27, in advance of the support-guide or housing, are rearwardly diverging support bars 35, rigidly attached thereto by 20 means of a bolt 36 or the like. These support bars diverge rearwardly, as stated, and are provided at their rear ends with extensions 37, which are preferably parallel and carry heads 38, having elongated slots 39. 25 These slots receive therein flanged rollers 40, pivotally supported by L-shaped brackets 41, which are rigidly attached to the forward edge of the transverse support bar 21.

The rear end of the drawbar 27 is suspended 30 from the transverse support yoke 42, see particularly Figures 5 and 9. The horizontal portion of this support yoke is clamped to the rear end of the drawbar 27 by means of a U-bolt 43. The yoke 42 is suspended 35 from the support bars 35, by means of U-bolts 44, carried thereby, and fitting in selected notches 45, as shown.

The numeral 46 designates lower connecting bars, which diverge rearwardly. These 40 connecting bars are preferably formed longitudinally adjustable, and for this purpose each bar may embody bar sections 47 and 48. The bar section 47 is slidable within a sleeve 49, formed upon the rear end of the bar section 48, and the bar sections may be clamped together at a selected longitudinal adjusted position by means of a bolt 50, as shown. The rear ends of the lower sections 47 are pivotally connected with the forward ends of 50 the sides of the scraping element, at points near and spaced from the bottom of the scraping element, as shown at 51. The forward ends of the bar sections 48 are rigidly secured to a carriage 52, embodying inverted 55 L-shaped members 53. Each inverted L-shaped member is preferably rigidly attached to the forward end of the bar member 48. The inverted L-shaped members 53 have their horizontal portions rigidly connected at points near their rear ends by 60 means of a transverse shouldered bolt 54, and these members carry an upper roller 55, suitably disposed between the same, and rotatably connected therewith. The roller 55 travels upon the top of the support-guide 24, 65

as shown. The lower ends of the inverted L-shaped members 53 are rigidly connected by means of a shoulder bolt 56, as shown.

In order that the carriage 52 may be held against longitudinal movement upon the support-guide 24, until it is desired to dump the load, such carriage is equipped with a locking bail or element 57, pivotally connected with the inverted L-shaped members 53, as indicated at 58. The bail 57 is urged 70 upwardly by retractile coil springs 60, attached thereto, and to the forward ends of the horizontal arms of the members 53, as shown. This bail is adapted to engage over the forward edge of a trip element 61, arranged between the forward ends of the sides of the support-guide 24, and pivoted thereto for swinging in a vertical plane, as indicated at 62. The pivot 62 is located at the extreme lower end of the trip element 61, and the bail 85 57 engages, in the locked position, with this trip element, above the pivot 62. The trip element 61 carries a pin or bolt 63, at its upper end, engaging with a retractile coil spring 64, which serves to normally retain 90 the trip element in the rear position, and to return the same to this position, when released. The trip element 62 is equipped with a roller 65, adapted to be engaged by a trip lever 66, which may be moved by a line, not 95 shown.

The numeral 68 designates an upper operating link or element, extending longitudinally above the support-guide or housing 24. This connecting link or element preferably embodies a pair of spaced bars 69, rigidly connected by shoulder bolts 70. The forward ends of the bars 69 are preferably curved downwardly, as indicated at 71, and these curved ends are pivotally connected 100 with the forward end of the guide-support or housing 24 by means of a shouldered bolt 72, and this bolt also carries the roller 31. The curved ends 71 are located within the support-guide, while the trip lever 66 is located exteriorly thereof, and this trip lever is also pivotally supported by the bolt 72. The operating connecting element or link 68, extends rearwardly, and is pivotally connected, at 73, with an upstanding lever 74, 110 the lower end of which is preferably forked, and is pivotally connected, at 75, with the rear end of the drawbar 27. The upper end of the lever 74 is pivotally connected, as shown at 76, with a hand lever 77. This hand lever is pivotally connected at its lower end, as shown at 78, with a rigid link or bar 79, which is preferably longitudinally adjustable. This link or bar extends rearwardly 115 and has pivotal connection with the transverse beam 21, at a point equidistantly spaced from the ends thereof, as shown at 80. The rigid bar or link 79 has a toothed quadrant 81, rigidly mounted thereon, for co-action with a latch 82, carried by the hand 120 125 lever 77. The latch 82 is pivotally connected with the support-guide 24, as shown at 83, and is urged into engagement with the toothed quadrant 81, by a coil spring 84, as shown at 85. The hand lever 77 is pivotally connected with the support-guide 24, as shown at 86, and is urged into engagement with the toothed quadrant 81, by a coil spring 87, as shown at 88. The hand lever 77 is pivotally connected with the support-guide 24, as shown at 89, and is urged into engagement with the toothed quadrant 81, by a coil spring 90, as shown at 91. The hand lever 77 is pivotally connected with the support-guide 24, as shown at 92, and is urged into engagement with the toothed quadrant 81, by a coil spring 93, as shown at 94. The hand lever 77 is pivotally connected with the support-guide 24, as shown at 95, and is urged into engagement with the toothed quadrant 81, by a coil spring 96, as shown at 97. The hand lever 77 is pivotally connected with the support-guide 24, as shown at 98, and is urged into engagement with the toothed quadrant 81, by a coil spring 99, as shown at 100. The hand lever 77 is pivotally connected with the support-guide 24, as shown at 101, and is urged into engagement with the toothed quadrant 81, by a coil spring 102, as shown at 103. The hand lever 77 is pivotally connected with the support-guide 24, as shown at 104, and is urged into engagement with the toothed quadrant 81, by a coil spring 105, as shown at 106. The hand lever 77 is pivotally connected with the support-guide 24, as shown at 107, and is urged into engagement with the toothed quadrant 81, by a coil spring 108, as shown at 109. The hand lever 77 is pivotally connected with the support-guide 24, as shown at 110, and is urged into engagement with the toothed quadrant 81, by a coil spring 111, as shown at 112. The hand lever 77 is pivotally connected with the support-guide 24, as shown at 113, and is urged into engagement with the toothed quadrant 81, by a coil spring 114, as shown at 115. The hand lever 77 is pivotally connected with the support-guide 24, as shown at 116, and is urged into engagement with the toothed quadrant 81, by a coil spring 117, as shown at 118. The hand lever 77 is pivotally connected with the support-guide 24, as shown at 119, and is urged into engagement with the toothed quadrant 81, by a coil spring 120, as shown at 121. The hand lever 77 is pivotally connected with the support-guide 24, as shown at 122, and is urged into engagement with the toothed quadrant 81, by a coil spring 123, as shown at 124. The hand lever 77 is pivotally connected with the support-guide 24, as shown at 125, and is urged into engagement with the toothed quadrant 81, by a coil spring 126, as shown at 127. The hand lever 77 is pivotally connected with the support-guide 24, as shown at 128, and is urged into engagement with the toothed quadrant 81, by a coil spring 129, as shown at 130.

lever. The hand lever 77 and associated elements constitute a longitudinally adjustable connection between the lever 74 and the transverse beam 21.

5 The operation of the apparatus is as follows:

At the starting loading operation, the scraping element 15 and associated elements assume the positions shown in Figures

10 2 and 3. A tractor, draft animals, or the like, is attached to the forward end of the draft bar 27, and the scraping apparatus is moved forwardly over the ground. The scraping element 15, is now inclined down-
15 wardly in a forwardly direction, whereby it will dig into the ground for a suitable distance, and the scraping operation is had, with the gradual filling of the scraping element.

As the scraping element approaches the load-
20 ed condition, its weight increases, and the pull forwardly upon the draw-bar 27 is op-
posed, by the pull rearwardly on the scrap-
ing element, due to the increased load. These
opposing forces will now compress the
25 spring, with the result that the support-
guide or housing 24 moves rearwardly upon
the draft bar 27. Upon this rearward move-
ment, the operating connecting link or bar
68 moves rearwardly, with respect to the

30 draft bar 27, and the operating lever 74 has
its upper end swung rearwardly. This moves
the rigid bar or link 79 rearwardly, and
hence the upper end of the scraper is swung
35 rearwardly, and the entire scraping element
is tilted rearwardly. This tilting action rear-
wardly, gradually progresses as the load
within the scraping element increases, until
the point is approached at which the scrap-
ing element would be overloaded. However,

40 the rearward tilting action has occurred suf-
ficiently, before the overloading point is
reached, whereby the forward connecting
edge of the scraping element is elevated suf-
ficiently, so that it will not take further load
45 or tilt. Upon the rearward movement of
the support-guide or housing 24, with re-
spect to the draw-bar, as above explained, the
lower connecting bars 46 move rearwardly
and the operating connecting link or element

50 68 moves rearwardly. However, the link 68
operates the lever 74 and elements connected
therewith, which will in turn move the upper
portion of the scraping element rearwardly
a greater distance than the lower bars are

55 moving the lower portion of the same rear-
wardly. This results in the rearward tilting
of the scraping element, as is obvious. In
other words, there is a differential action be-
tween the means which connects the lower

60 portion of the scraping element with the
support-guide and the means which con-
nects the upper portion of the scraping ele-
ment with the support-guide, and it is by
virtue of this differential action, that the

65 scraping element is tilted rearwardly, upon

the rearward movement of the support-guide
or housing. With the scraping element thus
properly loaded, the same may be dumped by
pulling upon the line 67, which will swing
the trip element 61 forwardly whereby the
70 bail 57 moves downwardly off of the then
inclined trip element. Further pull upon
the draft bar 27 will throw or roll the scrap-
ing element forwardly, to the dumping posi-
tion, as clearly illustrated in Figure 5.

75 It is to be understood that the form of my
invention herewith shown and described is
to be taken as a preferred example of the
same, and that various changes in the shape,
size, and arrangement of parts, may be re-
sorted to without departing from the spirit
80 of my invention, or the scope of the sub-
joined claims.

Having thus described my invention, what
I claim is:

85 1. In a scraping apparatus of the char-
acter described, a scraping element, a draw-
bar, a yielding element carried by the draw-
bar, and differential means connecting the
yielding element with the upper and lower
90 portions of the scraping element whereby
the scraping element may tilt rearwardly
upon the increase of the load therein.

95 2. In a scraping apparatus of the char-
acter described, a scraping element, a draft
element, yielding means connected with the
draft element, and differential means con-
necting the yielding element with the scrap-
ing element at spaced points for effecting
100 the tilting of the scraping element in one
direction as the load therein increases.

105 3. In a scraping apparatus of the char-
acter described, a scraping element, a draft
bar arranged in advance of the same, a mem-
ber mounted upon the draft bar to move
longitudinally thereof, yielding means to
oppose the rearward movement of the mem-
ber upon the draft bar, means connecting
the member with the lower portion of the
scraping element, a pivoted lever, means
connecting the pivoted lever with said mem-
ber, and means connecting the pivoted lever
with the upper portion of the scraping ele-
ment.

115 4. In a scraping apparatus of the char-
acter described, a scraping element, a draft
bar arranged in advance of the same, a mem-
ber mounted upon the draft bar to move
longitudinally thereof, yielding means to
oppose the rearward movement of the mem-
ber upon the draft bar, means connecting
the member with the lower portion of the
scraping element, a lever pivoted to the rear
portion of the draft bar, a connecting ele-
ment pivoted to the lever between its ends
and pivoted to said member, and means con-
necting the opposite end portion of the lever
with the upper portion of the scraping ele-
ment.

120 5. In a scraping apparatus of the char-

acter described, a scraping element, a draft bar arranged in advance of the same, a support-guide slidable longitudinally upon the draft bar, yielding means to oppose the rearward movement of the support guide upon the draft bar, a carriage movable longitudinally upon the support-guide, releasable means for locking the carriage upon the support-guide against rearward longitudinal movement, connecting means between the carriage and the lower portion of the scraping element, an upstanding lever pivoted at its lower end to the rear portion of the drawbar, a link connected with the intermediate portion of the lever and connected with the support-guide, and means connecting the upper portion of the lever with the upper portion of the scraping element.

6. In a scraping apparatus of the character described, a scraping element, a transverse support connected with the upper portion of the same, a drawbar arranged in advance of the scraping element, a guide-support slidable upon the drawbar, a spring to oppose the rearward movement of the guide-support upon the drawbar, a carriage slidable upon the guide-support, releasable means to prevent the longitudinal movement of the carriage upon the guide-support, means connecting the carriage and the lower portion of the scraping element, supporting bars attached to the forward end of the drawbar and extending rearwardly and hav-

ing a slidable connection with the transverse support, means supporting the rear end of the drawbar from the supporting bars, an upstanding lever pivoted upon the rear portion of the drawbar, a link pivoted to the intermediate portion of the lever and pivoted to the guide-support, and means connecting the upper portion of the lever with the transverse support.

7. In a scraping apparatus of the character described, a scraping element having runners arranged in advance of the same, a transverse beam mounted upon the upper portion of the runners, a drawbar in advance of the scraping element, a housing slidable upon the drawbar, a spring upon the drawbar within the housing to oppose the rearward movement of the housing upon the drawbar, a carriage movable longitudinally upon the housing, a latch to connect the carriage with the forward end of the housing, means to trip the latch, means connecting the carriage with the lower portion of the scraping element, supporting means suspended from the transverse beam and connected with the rear portion of the drawbar and the forward portion of the drawbar, a pivoted lever, means connecting the lever with the housing, and means connecting the lever with the transverse beam.

In testimony whereof I affix my signature.

GEORGE D. WEAVER.
